UNITED STATES PATENT OFFICE.

EARL H. ARBUTHNOT, OF FLORA, ILLINOIS.

CLAMP.

Application filed June 28, 1922. Serial No. 571,445.

To all whom it may concern:

Be it known that EARL H. ARBUTHNOT, a citizen of the United States, residing at Flora, in the county of Clay and State of Illinois, has invented certain new and useful Improvements in Clamps, of which the following is a specification, reference being had to the accompanying drawings.

This invention relates to certain improvements in basket clamps and it is a primary object of the invention to provide a novel and improved device of this general character especially designed and adapted for use in holding a cover or closure member to a basket.

Another object of the invention is to provide a novel and improved device of this general character comprising a member of bendable material provided at its extremities with hook members and wherein the intermediate portion of the member is provided with means adapted to be engaged with a suitable tool to cause the hooks to effectively engage the work.

The invention consists in the details of construction and in the combination and arrangement of the several parts of my improved basket clamp whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein:

Figure 1 is a fragmentary view in elevation illustrating a basket clamp constructed in accordance with an embodiment of my invention and in applied position;

Figure 2 is a fragmentary elevational view illustrating my improved clamp before the same has been pressed into locking engagement;

Figure 3 is a view in side elevation of a clamp as illustrated in Figures 1 and 2;

Figure 4 is an elevational view of a clamp constructed in accordance with a further embodiment of my invention; and

Figure 5 is a view in side elevation of a clamp as illustrated in Figure 4.

As disclosed in the accompanying drawings, 1 denotes the upper hoop or ring com-

prised in a basket of a conventional bushel type and 2 denotes the hoop or ring comprised in the edge or margin of the top or closure T for the basket.

60

C denotes a clamp constructed in accordance with an embodiment of my invention which is formed of wire or other strand 3 of bendable material possessing requisite strength. The extremities of this strand 3 are returned to provide the inwardly facing hooks 4, the bills of which being sharpened as at 5.

65

The strand 3 intermediate the hook members 4 and preferably centrally thereof is bent to provide the oppositely directed lateral extensions 6 each herein disclosed as substantially semi-circular in form. Initially the hook members 4 are spaced apart a distance to permit the same to be properly engaged with the hoops or rings 1 and 2 whereupon an extension 6 is engaged by a pair of pliers or other suitable tool and the side members of said extension 6 pressed together, resulting in the hooks 4 being caused 70 to firmly engage the hoops or rings 1 and 2. When the clamp C is applied the extension 6 is substantially parallel to the adjacent wall of the basket proper so that the same does not extend outwardly to offer any hindrance 75 or inconvenience in the handling, carting, loading or transporting of the basket as by coming in contact with the hands and clothing of the workmen or other objects. The flattened bills 5 of the hooks 4 facilitate the 80 proper application of the hooks 4.

85

By providing the oppositely directed extensions 6 said extensions need not be of any considerable size so that the application of the pliers is facilitated and at the same time 90 reducing to a minimum the possibility of the pliers slipping off when being applied. By having these extensions 6 relatively small the strength of the clamp is materially increased.

95

As disclosed in Figure 4, is illustrated an embodiment of my invention wherein the clamp C' is provided with a single lateral extension 6 also substantially semi-circular in form. The application of this embodiment of my clamp is substantially the same as hereinbefore set forth in the type of clamp as described.

100

The present application is partly in continuation of my former application Serial No. 552,049 filed April 12, 1922.

From the foregoing description it is

thought to be obvious that a basket clamp constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

15. I claim:

1. A basket clamp comprising an elongated member of bendable material having inwardly facing hooks at its opposite ends, said hooks being laterally disposed with respect to the elongated member and positioned at the same side thereof, said member being provided with means whereby the hooks can be drawn one toward the other through the medium of applied pressure, said means comprising a lateral extension of the member, said extension having spaced side arms.

2. A basket clamp comprising an elongated member of bendable material having inwardly facing hooks at its opposite ends, said hooks being disposed laterally with respect to the member and at the same side thereof, the member intermediate the hooks having a lateral extension provided with spaced side arms, the lateral extension being angular with respect to the lateral disposition of the hooks.

3. A basket clamp comprising an elongated member of bendable material having inwardly facing hooks at its opposite ends, said hooks being disposed laterally with respect to the member and at the same side thereof, the member intermediate the hooks

having a lateral extension provided with spaced side arms, the lateral extension being angular with respect to the lateral disposition of the hooks, the bills of the hooks being sharpened.

4. A basket clamp comprising an elongated member of bendable material having inwardly facing hooks at its opposite ends, said hooks being disposed laterally with respect to the member and at the same side thereof, the member intermediate the hooks having a lateral extension provided with spaced side arms, the lateral extension being angular with respect to the lateral disposition of the hooks, the bills of the hooks being sharpened, the edges of the bills being disposed in the same general direction as the lateral extension of the member.

5. A basket clamp comprising an elongated member of bendable material having inwardly facing hooks at its opposite ends, said hooks being laterally disposed with respect to the elongated member and positioned at the same side thereof, and with said member intermediate the hooks having opposite disposed lateral extensions provided with spaced side arms, the lateral extensions being angular with respect to the lateral disposition of the hooks.

6. A basket clamp comprising an elongated member of bendable material having inwardly facing hooks at its opposite ends, said hooks being disposed laterally with respect to the member and at the same side thereof, the member intermediate the hooks having lateral extensions provided with spaced side arms, the lateral extension being angular with respect to the lateral disposition of the hooks.

In testimony whereof I hereunto affix my signature.

EARL H. ARBUTHNOT.
